UNITED STATES PATENT OFFICE.

WILBUR F. DROWN, OF WASHINGTON, DISTRICT OF COLUMBIA.

GAME.

Application filed April 10, 1923. Serial No. 631,244.

To all whom it may concern:

Be it known that WILBUR F. DROWN, citizen of the United States, residing at 1027 12th St. NW., city of Washington, in 5 the District of Columbia, has invented certain new and useful Improvement in Games, of which the following is a specification, reference being had therein to the accompanying drawing.

10 My invention relates to games and more particularly to a fortune telling device.

The main object of the invention is to provide a fortune telling device founded on the principle that fortunes depend upon 15 a number of factors, for example, desire, personality and will, and arranged to operate to indicate chance combinations of a variety of examples of such factors.

Another object is to provide a device of 20 the above character which may be readily understood and operated with a minimum amount of mental and physical effort, or previous instruction.

Various other objects of the invention 25 will be apparent from a perusal of the following specification and the drawings accompanying the same.

In the drawings:

Fig. 1 is a plan view.

30 Fig. 2 is a section on the line 2—2 of Fig. 1.

Referring to the drawings in detail, 1 is a box or container in which a plurality of 35 rectangular cards 2, 3, 4, and 5 are arranged one above the other, the lower card covering the bottom of the box and the superimposed cards 3, 4, and 5 having circular openings in their centers progressively increasing in size from the bottom up, so as to expose 40 ring-shaped areas B and C on the interposed cards 4 and 3, respectively, with the opening of the upper card 5.

On the lower card 2, concentric with the openings in the superimposed cards, is 45 mounted a spindle post 6 on which is pivoted a number of indicating hands 7, 8 and 9, extending slightly over the edges of the openings in the cards 3, 4, and 5, respectively, the hands being suitably separated by washers 10, to allow of independent movement.

The cards 3, 4, and 5 are divided circumferentially of their opening by radial lines 50 to form a plurality of circularly arranged divisions on which are printed expressions of different variants of the factors represented by the different cards. For example, the inner circle on card 3 bears expressions relating to the will, the middle circle on card 4 bears expressions relating to 60 the personality while the outer card bears matter relating to desire.

To operate the device, the hands are simply spun around by a quick movement of the hand of the operator, allowing them 65 to stop where they may and the fortune read off from the spaces on the different cards where the hands stop.

In combination with the readings, the spaces on the different cards are also numbered consecutively in two colors, say red 70 and black, distinguished in the drawing by solid and dotted lines respectively, a pair of red numbers alternating with a single black number so as to have twice as many 75 red numbers as there are black numbers. This differentiation in the color of the numbers is used for wishing in which use of the device the probability of obtaining the wish is determined by spinning the hands and 80 interpreting the color combinations as follows:

1. If all of the hands stop at red numbers, you will get your wish fully and soon.
2. If two hands stop at red and one at 85 black, you will get your wish after some delay.
3. If two hands stop at black and one at red, you may get your wish, but it is doubtful.
4. If all the hands stop at black, you will 90 not get your wish.

For reading fortunes by birth date, the hands are placed without whirling as indicated below for the different dates and the 95 spaces there indicated read off.

Aug. 22 to Sep. 21,	A 9	B 5	C 6
Sep. 22 to Oct. 22,	A 10	B 7	C 3
Oct. 23 to Nov. 21,	A 11	B 9	C 2
Nov. 22 to Dec. 20,	A 12	B 11	C 1
Dec. 21 to Jan. 19,	A 1	B 12	C 4

To avoid complexity in the drawings only three of the readings in the different spaces 110 are shown, but it is to be understood that other readings should appear in all the other spaces, for example as follows:

larly arranged spaces on said dial cards bearing inscriptions representing different factors of a fortune.

2. A game of the class described comprising a plurality of concentric dials, centrally countersunk in steps, a plurality of indicating hands of different lengths, one for each step overlying each dial all pivoted centrally of the dials and arranged to be spun independently of each other, and divisions on said dials bearing representations of different elements of a fortune, the elements of any one given dial relating to a common subject and each dial containing elements relating to different subjects.

3. A game of the class described comprising a plurality of vertically spaced spinning hands of different lengths arranged to be spun all at the same time and to move independently of each other, the shortest at the bottom and the longest at the top, and a dial for each hand having divisions thereon bearing representations of specific examples of different topics of a fortune, each dial bearing specific examples of a common topic, and all the dials being arranged on steps corresponding to the levels of the several hands.

4. A game of the class described comprising three chance controlled selecting devices arranged to be simultaneously operated each to select any one of a plurality of different elements of a fortune, the elements representing different variants of a factor of a fortune and arranged in three groups, one for each indicating device, each group containing variants of the same factor, the mechanical structure for this arrangement comprising fixed dials with three countersunk steps, a central vertical spindle reaching above the highest step, and three pointers or hands freely movable on said spindle, at three different levels and of three different lengths so they may point out indications on their respective dials in the countersunk steps.

5. A game device comprising circular indicia-bearing cards forming a circular stepped well, and a central spindle carrying hands in said well, one hand for each card and at the level of that card, the indicia being in separate sets, one for each card, and the hands separately movable.
